WORK EJECTOR FOR MACHINE TOOLS

Ralph E. Price, Highfield, Md., assignor to
Landis Tool Company, Waynesboro, Pa.

Application April 21, 1949, Serial No. 88,811

7 Claims. (Cl. 51—103)

1

This invention relates to apparatus for ejecting finished work pieces from machine tools, particularly centerless grinders.

The principal object of this invention is to provide and ejecting mechanism operable in timed relation with the feeding movement of the machine and which resets itself immediately after functioning to remove a work piece from the machine.

A further object is to provide a valve mechanism for controlling the operation of the ejector in accordance with the operation of the feeding mechanism of the machine.

Figure 1 is a diagrammatic sketch of the essential elements of this invention.

Numerals 10 is a wheelbase having a grinding wheel 11 rotatably mounted therein. Said wheelbase may be slidably mounted transversely of the axis of said wheel on any suitable type of bed member (not shown). Peripherally opposed to grinding wheel 11 is a control wheel 12. In the space between the peripheral spaces of said wheels, a work piece 13 may be inserted and supported in a manner well known to those skilled in the art of centerless grinding.

The means for effecting transverse movement of wheelbase 10 consists of a cylinder 20, a piston 21 slidably mounted therein, a piston rod 22 having a threaded portion 23 in operative engagement with a worm wheel 24 on feedscrew 25. These parts are all supported in wheelbase 10, as shown more in detail in Balsiger et al. Patent 2,419,940, granted May 6, 1947, and my co-pending application Ser. No. 46,280, filed August 26, 1948, and which issued as Patent No. 2,571,610 on October 16, 1951.

Said feedscrew 25 is threaded in a nut 26, secured to said above-mentioned bed member. A hand wheel 30 is connected through suitable gearing to rotate piston rod 22 with the threaded portion thereof acting as a worm gear instead of a rack.

The means for supplying the fluid under pressure to cylinder 20 consists of a pump 35 which supplies fluid under pressure through line 36 to valve 37. Said valve directs said fluid alternately through lines 38 and 39 to opposite ends of cylinder 20.

The ejector mechanism consists of an ejector plunger 50 slidably supported in a bracket 51 and held in inoperative position by spring 52, as shown in the drawing. The means for actuating said plunger consists of a piston 55 slidably mounted in a cylinder 56 and having a piston rod 57 abutting one end of a lever 58, the other end of

55 being connected to a lever 59 for ejecting finished work pieces from the machine. Lever 59 is pivoted at 60 and has a slot 61 for receiving the end of piston 55. Lever 59 is biased by spring 52 to a position in which piston 55 is held in a position to eject work pieces from the machine. Lever 59 is also biased by spring 62 to a position in which piston 55 is held in a position to eject work pieces from the machine.

2

which is attached to plunger 50. Said lever is pivoted at 59.

Piston 55 is actuated in one direction by fluid under pressure, preferably air, controlled by a pair of valves 65 and 66 mounted in tandem in a housing 67 divided into two parts by a partition member 68. Valve 65 has a stem portion 70 in the path of movement of lever 58. Valve 66 also has a stem member 71 passing through partition 68 into engagement with valve 65.

Valve 66 is shifted in opposite directions by fluid under pressure supplied alternately to the right end thereof from line 38 through line 80, and to the other end of said valve from cylinder 20 to which it is connected by line 81.

Air is supplied to valve 66 through line 90. With said valve shifted to the right, air is directed through line 91 to valve 65, which in turn directs it through line 92 to the head end of cylinder 56.

Operation

With the parts in the position shown, fluid under pressure is directed from pump 35 through line 36 and valve 37 through line 39 to the head end of cylinder 20. Piston 21 in cylinder 20 is thus caused to move to the right. This movement serves to rotate feedscrew 25, which in turns causes wheelbase 10 and grinding wheel 11 to move away from the grinding position shown. As piston 21 moves to the right, it uncovers passage 81 through which fluid under pressure flows to the left end of valve 66, shifting said valve to the right and connecting air supply line 90 with line 91. Air flows through line 91, valve 65 and line 92 to the head end of cylinder 56, causing piston 55 and piston rod 57 to move to the right. Piston rod 57 engages lever 58, causing it to move in a counterclockwise direction, thus moving plunger 50 to the left against spring 52 and pushing the finished work piece 13 out of the grinding throat formed between the wheels 11 and 12.

As lever 58 continues to move in a counterclockwise direction, it engages the stem 70 of valve 65, shifting said valve to the right and connecting line 92 with exhaust line 95. With the fluid under pressure in the left end of cylinder 56 thus released, spring 52 returns plunger 50, lever 58 and piston 55 to the starting position so that another work piece may be inserted between wheels 11 and 12.

In order to return grinding wheel 11 to grinding position, valve 37 is shifted to the left to direct fluid under pressure from line 36 through line 38 to the rod end of cylinder 20 and also through line 80 to the right-hand end of valve 66.

Before wheelbase 10 begins to move, valve 66 is shifted to the left to block the flow of air from line 90 to line 91. During this movement of valve 66, the stem 71 thereon engages valve 65 shifting it to the left to connect line 91 with line 92 in readiness for the next ejecting operation.

I claim:

1. In a machine tool, a support slidably mounted for movement toward and from operative position, power means for effecting said movement including a piston and cylinder, a supply of fluid under pressure therefor, a work ejecting mechanism and connections between said cylinder and said work ejecting mechanism including a pressure-operated shut-off valve for the 15 ejector fluid, a second valve for directing said fluid to said ejector, and means responsive to actuation of said ejector for shifting said second valve to permit resetting of said ejector.

2. In a machine tool, a support slidably mounted for movement toward and from operative position, power means for effecting said movement including a piston and cylinder, a supply of fluid under pressure therefor, a work ejecting mechanism and connections between said cylinder and said work ejecting mechanism including a pressure-operated valve having connections with opposite ends of said cylinder, said valve being actuated at the beginning of said movement for cutting off the supply of fluid for 20 said ejector and a second valve actuated by movement of said first-mentioned valve to a position for directing fluid to said ejector when said fluid is available from said first valve.

3. In a grinding machine, a grinding wheel support, a piston and cylinder, one of which is attached to said support for moving a grinding wheel toward and from operative position, an ejecting mechanism for removing a work piece from the machine, a motor comprising a piston and cylinder for actuating said ejector, means for actuating said ejector motor, including a pair of valves, one of which is actuated in timed relation with said feed movement, the other of which is actuated in one direction by said ejector and in the opposite direction by the movement of said first-mentioned valve.

4. In a machine tool, a support slidably mounted for a movement toward and from operative position relative to a work piece, a cutting tool on said support, power means for effecting said movement including a piston and cylinder, a supply of fluid under pressure therefor, a work ejecting mechanism, and connections between said cylinder and said work ejecting mechanism for actuating said mechanism, including a valve in the path of movement of said ejector actuating means and operable for first directing fluid under pressure to actuate said ejector and operable by 50 said ejector in response to movement of said

ejector in ejecting a work piece, for thereafter directing said fluid to reset said ejector.

5. In a machine tool, a feed mechanism comprising a piston and a cylinder, one of which is attached to a part to be moved, a work ejecting mechanism comprising an ejector rod, resilient means for holding said ejector rod in inoperative position, a piston and cylinder for actuating said ejector rod against the action of said resilient means, means for supplying fluid under pressure to said piston including a valve in substantial axial alignment with said ejector piston, and a connecting means between said valve and said piston whereby actuation of said piston shifts said valve to permit resetting of said ejector.

6. In a machine tool, a feed mechanism comprising a piston and a cylinder, one of which is attached to a part to be moved, a work ejecting mechanism comprising an ejector rod, resilient means for holding said ejector rod in inoperative position, a piston and cylinder for actuating said ejector rod against the action of said resilient means, means for supplying fluid under pressure to said piston including a valve in substantial axial alignment with said ejector piston, a second valve in alignment with said first mentioned valve, connections from said second valve to opposite ends of said feed cylinder, said second valve in one position being effective to connect the supply of fluid under pressure with said first mentioned valve and in another position to cut off said supply of fluid under pressure with said first mentioned valve, a stem on said second valve for engaging and shifting said first valve when said second valve is shifted in one direction by fluid under pressure from said feed cylinder, whereby to reset said valves in preparation for another actuation of said ejector.

7. In a machine tool, a feed mechanism, a work ejecting mechanism comprising an ejector rod, resilient means for holding said ejector rod in inoperative position, a piston and cylinder for actuating said ejector rod against the action of said resilient means, means for supplying fluid under pressure to said piston including a valve in substantial axial alignment therewith, said valve being actuated by movement of said ejector piston in ejecting a work piece to connect the fluid line to said piston with an exhaust passage.
